PUMP OR MOTOR STRUCTURE

Charles E. Broman, Algoma Township, Kent
County, Mich.

Application May 16, 1936, Serial No. 80,065

4 Claims. (CL. 103—136)

The present invention relates to rotary pump or fluid-driven motor structures; and its object is, generally, to provide such a structure improved in respects hereinafter appearing; and particularly, to provide such a structure which shall operate continuously, and very steadily and noiselessly; and further, to provide such a structure in which the driving power is exerted with great effect; and further, to provide in such a structure a well balanced rotor; and further, to provide such a structure in which friction may be diminished; and further, to provide such a structure having a circuitous channel comprising angularly disposed portions into which the fluid is continuously and simultaneously admitted into operative contact with the pistons therein and from which the fluid is vented in like manner; and further, to provide such a structure wherein the pistons are moved by the structure's operation into said portions of the channel alternately; and further, to provide in such a structure improved pistons.

These and any other and more specific objects hereinafter appearing are attained by, and the invention finds preferable embodiment in, the illustrative structure particularly described in the body of this specification and illustrated by the accompanying drawing, in which:—

Figure 1 is an elevational view of a pump or motor structure embodying my invention, with the fluid intake pipe removed;

Figure 2 is a right hand-side view of the structure with the cover plate removed;

Figure 3 is a sectional view of the same, with the cover plate in place, taken on the diametrical line 3—3 of Figures 2 and 4;

Figure 4 is a sectional view thereof taken on line 4—4 of Figure 3;

Figure 5 is a sectional view of the same taken on line 5—5 of Figures 1 and 3;

Figure 6 is a right hand-side view, with the cover plate removed and certain parts broken away to show a modified construction of the pistons;

Figure 7 is a right hand-side view similar to Figure 2 but showing a slightly modified construction in which the fluid intake is in another angular position.

The body or casing 1 of the pump or motor structure illustrated by the drawing mounted as by bolts 2 on a suitable base has a chamber 3 with fluid intake port 4 and discharge port 5 and provided with a circular cover plate 6 removably held in place by screws 7. This cover plate has an inwardly extending circular rib 8 fitting inside the concentric flange 9 of the casing, and

has in its inner side a circular concentric recess bearing 10. From the bottom 11 of the casing's chamber 3 a member 12 extends outwardly having a journal bearing 13.

This member 12, as shown, is formed of a separate piece seated in a curved rabbet 14 and is held in place by pins or screws 15. Said member's curved inner side and the curved side of the casing form the circuitous chamber 3 between them of uniform width throughout. One portion 10 of this chamber extends from the rotary axis of the structure farther than the opposite portion thereof extends. To effect this, the chamber is approximately ovate having a portion 16 whose parallel circular sides 17, 18 are spaced nearer 15 said axis than are the circular sides 19, 20 of the chamber's opposite portion 21, these circular portions being concentric and connected by elliptical portions 22 of the chamber.

The shaft 23 rotatably bears at 24, 25 in the 20 casing 1 and in its cover plate 6 and extends tightly through the concentric circular rotor 26 keyed thereto. The rotor's flat outer side rotatably bears in the cover plate's recess 10, its hub portion 28 bearing in bearing 13 of the member 12, and its inwardly extending concentric circular rib or flange 29 bearing on the bottom of the casing's chamber 3. The outer curved side 30 of the rotor's said rib is adjacent and as shown rotatably bears on the circular side 17 of portion 16 of said chamber while the inner curved side 31 of said rib is adjacent and as shown rotatably bears on the circular side 19 of the chamber's opposite portion 21.

The rotor carries pistons extending across and fitting in the chamber. These pistons 32 as shown in Figures 2, 3, 4 and 7 are of cylindrical form (hollow to minimize weight) fittingly seated and turnably bearing in openings or gaps 33 through said rib. These pistons' diameters equal the width of the chamber and of said openings, in which they are freely moved or "cammed" radially of the rotor by the chamber's portions 22 into or out of its said circular portions 16 or 21 so as to bear at their opposite sides on the opposite curved sides of the chamber in all rotated positions of the rotor, their ends bearing on the flat bottom of chamber 3 and on the flat inner side of the rotor.

It will be seen that the chamber's circular portions 16 and 21 form semicircular fluid channels in which the fluid passes along the inner side of the rotor's rib in channel 16 and along the rib's outer side in channel 21, the fluid passing along 55

both sides of the rib in the portions 22 of the chamber.

By passages branching between the structure's intake port 4 and discharge port 5 the fluid is continuously admitted to and vented from both of said opposite portions 16, 21 of said chamber. Into one of these passages the fluid is admitted at its inlet 35 from the structure's intake port 4 directly into portion 21 of the chamber through 10 its curved outer side and operatively contacts that side portion of the pistons which extends outwardly from the rotor's rib 29 into said portion 21, from which portion the fluid is vented at 36 into the structure's discharge port 5.

15 The other passage admits fluid from its inlet 37 from the structure's intake port 4 whence it passes into this passage's portion 38 and semi-circular portion 39 in the casing behind the member 12 and thence through said member's opening 20 40, which extends from its flat bottom 41 through its curved side, into the chamber's portion 16 wherein the fluid operatively contacts that side portion of the pistons which extends inwardly from the rotor's rib 29 into the chamber's said 25 portion 16, from which the fluid is vented through said passage's opening 42, which extends from the curved side of member 12 through its bottom, and through the semicircular portion 43 and portion 44 of said passage in the casing behind member 12 and is vented at 45 into the structure's discharge port 5.

The member 12 thus forms a transaxial partition between chamber 3 and the passages behind this member.

35 In Figure 6 pistons 32¹ of a usual form are shown extending through the rotor's rib 29 and turnably mounted at their smaller ends.

In Figure 7 the structure's intake pipe 50¹ is disposed at an angle of about 30 degrees above 40 the intake pipe 50 of other views, the inlet 35¹ therefrom extending as indicated in dotted lines to the chamber's portion 21, thus better adapting the structure to its use as a motor by avoiding shutting off the fluid by the rotor's rib 29 from 45 entering into the chamber from said inlet.

The structure's discharge pipe is shown at 51, stuffing boxes at 52, a wear washer at 53 and a packing ring 54 seated in an annular groove in the cover plate.

50 It will be seen that the operation of this pump or motor is very continuous, noiseless and steady and that the rotor is well balanced, the fluid being continuously admitted and vented from portions of the chamber simultaneously which 55 are on opposite sides of the axis of rotation; that the power is thus very effectively applied; and that the turnable pistons tend to reduce friction.

The invention being intended to be pointed out in the claims, is not to be limited to or by details 60 of construction or arrangement of any particular embodiment thereof illustrated by the drawing or hereinbefore shown or described.

I claim:

1. In a pump or motor structure of the class 65 described: a rotor having a hub with the rotor shaft secured thereto and a concentric circular rib; a casing having a circuitous chamber with a curved side wall comprising circular arcual portions concentric with and at different radial distances respectively from the shaft, and arcual portions connecting said circular portions; a member 70 detachably secured in the bottom of the chamber having a bearing wherein the rotor's hub rotatably bears, and a curved peripheral side comprising concentric circular arcual portions 75

uniformly spaced from and registering angularly with corresponding circular portions respectively of the chamber's side wall, said rib having gaps therethrough and being radially narrower than the chamber, extending therein and rotatably bearing at one of its curved sides on one of the circular portions of the chamber's side wall and at its other curved side rotatably bearing on the opposite circularly curved portion of said member throughout extended arcs of contacts respectively, thus forming a pair of angularly spaced circular arcual fluid channels in the circuitous chamber at opposite sides respectively of the rib, one of the channels having angularly spaced inlet and outlet ports; cylindrical pistons axially parallel with said shaft, fitting in said gaps and movable sidewise therein into said channels alternately in closing relation therewith, the casing having also fluid passages formed therein and separated from the bottom of the chamber by 20 said member and communicating through said member with the other channel for providing a continuous flow of the fluid through the structure as governed by the rotor's rotation.

2. In a pump or motor structure of the class 25 described: a rotor having a concentric circular rib; a casing having a circuitous chamber of uniform radial width with a curved side wall comprising circular arcual portions concentric with and at different radial distances respectively 30 from the rotor's axis, and arcual portions connecting said circular portions; a member in the chamber having a curved peripheral side comprising concentric circular arcual portions and arcual portions connecting the same, all said 35 arcual portions of said member's side being spaced from and registering angularly with corresponding arcual portions respectively of the chamber's side wall, said rib having gaps therethrough and being radially narrower than the 40 chamber, extending therein and rotatably bearing at one of its curved sides on one of the circular portions of the chamber's side wall and at its other curved side rotatably bearing on the opposite circularly curved portion of said member, and spaced from both sides of the chamber 45 in said connecting portions of its side wall, thus forming a pair of angularly spaced fluid channels in the circuitous chamber on opposite sides respectively of the rib, one of the channels having angularly spaced inlet and outlet ports; cylindrical pistons axially parallel with the rotor's axis, of a diameter equal to the width of the chamber and of the gaps and movable sidewise in the gaps into said channels alternately in 50 closing relation therewith; the casing having also fluid passages inwardly from the bottom of the chamber and communicating with the other channel for providing a continuous flow of the fluid along opposite sides of the rib in said channels respectively and along both sides of the rib in the portions of the chamber which connect said channels, as governed by the rotor's rotation.

3. In a pump or motor structure of the class 65 described: a rotor having a side forming one flat wall of the hereinafter mentioned chamber and an inwardly projecting concentric circular rib; a casing having a circuitous chamber with a curved side wall comprising circular arcual portions 70 concentric with and at different radial distances respectively from the rotor's axis and arcual portions connecting said circular portions; a member in the bottom of the chamber having a curved peripheral side comprising circular arcual por- 75

tions and arcual portions connecting the last named circular arcual portions, all said arcual portions of said member's side being spaced from and registering angularly with corresponding arcual portions respectively of the chamber's side wall, said rib being radially narrower than the chamber and extending therein and rotatably bearing at one of its curved sides on one of the circular portions of the chamber's side wall 10 and at its other curved side rotatably bearing on the opposite circularly curved portion of said member throughout extended arcs of contacts respectively, thus forming a pair of angularly spaced fluid channels in the circuitous chamber 15 at opposite sides respectively of the rib, one of the channels having angularly spaced inlet and outlet ports; pistons carried by the rotor and movable into said channels alternately in closing relation therewith, the casing having also 20 fluid passages inwardly of and separated from the bottom of the chamber and communicating with the other channel for providing a continuous flow of the fluid along opposite sides of the rib in said channels respectively as governed by 25 the rotor's rotation.

4. In a pump or motor structure of the class described: a rotor having a concentric circular

rib; a casing having a circuitous chamber of uniform radial width with a curved side wall comprising circular arcual portions concentric with and at different radial distances respectively from the rotor's axis, and arcual portions connecting said circular portions; a member in the chamber having a curved peripheral side comprising concentric circular arcual portions and arcual portions connecting the same, all said arcual portions of said member's side being 5 spaced from and registering angularly with corresponding arcual portions respectively of the chamber's side wall, said rib being radially narrower than the chamber, extending therein and rotatably bearing at one of its curved sides on 10 one of the circular portions of the chamber's side wall and at its other curved side rotatably bearing on the opposite circularly curved portion of said member, and being spaced from both sides of the chamber in the arcual portions of 15 the chamber which connect the circular portions thereof, thus forming angularly spaced fluid channels in the circuitous chamber on opposite sides respectively of the rib; pistons carried by the rotor movable into the channels alternately 20 25 in closing relation therewith.

CHARLES E. BROMAN.
